UNITED STATES PATENT OFFICE.

CHARLES DE WITT, OF BALTIMORE, MARYLAND.

DESIGN FOR A BOTTLE.

SPECIFICATION forming part of Design No. 24,464, dated July 9, 1895.

Application filed May 28, 1895. Serial No. 551,006. Term of patent 7 years.

To all whom it may concern:

Be it known that I, CHARLES DE WITT, a citizen of the United States, residing at Baltimore, State of Maryland, have invented and produced a new and original Design for Bottles, of which the following is a specification.

My invention relates to designs for bottles; and it consists in the novel shape for bottles shown in the accompanying drawings and hereinafter described and claimed.

In the drawings, Figure 1 is a side elevation of a bottle shaped according to my design. Fig. 2 is a vertical sectional view on the line 2 2, Fig. 1. Fig. 3 is a perspective view showing the formation of the shoulders. Fig. 4 is a transverse sectional view on the line 4 4, Fig. 1.

My design consists, essentially, in a low flat bottle having the short sides A rising vertically from the bottom and the long sides A', giving the bottle a squat appearance, of

elongated cross-section and surmounted by a neck B, which is joined onto the drooping shoulders by a slight curve. The shoulders distinctly droop on four sides, being bounded by segmental curves or the arches a, capping the tops of the four sides, meeting at points b at the corners, while the central lines C and C', joining the apexes of the arches with the neck, are substantially straight, the whole presenting the appearance shown.

I claim as my invention—

The design for a bottle, substantially as herein described and illustrated in the accompanying drawings.

In testimony whereof I have signed my name to this specification in the presence of two subscribing witnesses.

CHARLES DE WITT.

Witnesses:

WILLIAM H. BERRY,
MURRAY HANSON.
